UNITED STATES PATENT OFFICE.

MALCOLM CURRY, OF HOLYOKE, MASSACHUSETTS.

FURNACE.

1,292,586.

Specification of Letters Patent. Patented Jan. 28, 1919.

Application filed December 22, 1917. Serial No. 208,402.

To all whom it may concern:

Be it known that I, MALCOLM CURRY, a citizen of the United States, and resident of Holyoke, county of Hampden, and State of Massachusetts, have invented certain new and useful Improvements in Furnaces, of which the following is a specification.

This invention relates to improvements in furnaces and has for its principal object the provision of means whereby the condition of the fuel bed may be ascertained without opening the door of the fire-box.

A further important object of the invention is to provide means whereby the fireman or stoker may readily and clearly inspect the fuel bed without being subjected to the heat from the combustion chamber or fire-box.

Another object of the invention is to provide the fire-box with a transparent panel or section movable opposite and away from an aperture in the wall of the fire-box, to permit the stoker to inspect the fuel bed when desired, through said panel and to permit said panel to be normally moved to a position in which it is protected from the direct heat of the fire.

Another important object is to provide a fire-box with an observation opening and to provide means whereby said opening may be covered by either a transparent sheet, plate or panel, or by an opaque plate or panel of heat-resisting material such as iron or steel.

A further important object of the invention is to provide means for simultaneously shifting a section of the casing and protecting lining of a furnace to form an observation opening to permit inspection of the fuel bed, and to cover the opening thus formed with a plate, panel, or sheet of transparent material.

Another important object of the invention is to provide a transparent observation panel or section for a furnace casing, formed of blue glass or other suitable material adapted to eliminate the yellow rays to permit clear observation of the condition of the fuel bed.

In the drawings, Figure 1 is a front elevation of a furnace door equipped with one form of observation means, illustrating the preferred embodiment of the invention, the parts being shown in their normal position in which the observation opening is closed by the opaque plate or section;

Fig. 2 an enlarged fragmentary front ele-

vation, showing the transparent panel covering the observation opening;

Fig. 3 a fragmentary vertical transverse section, the parts being in the position shown in Fig. 1;

Fig. 4 a view similar to Fig. 3, the parts being in the position shown in Fig. 2; and

Fig. 5 an enlarged fragmentary rear elevation, the parts being in the position shown in Figs. 2 and 4.

While I prefer to employ the observation means in connection with the fire door of a furnace, as shown, it will be obvious that the observation means may be provided at any other suitable point in the furnace casing.

In the accompanying drawings, 1 designates a furnace fire door of well-known construction, connected with the body portion 75 of the casing 1^a by the usual hinges 2, and provided with the usual damper 3 and handle 4. The door is provided with a perforated protecting lining 5 held thereto in spaced relation with the inner face of the 80 door. The lining 5, except as hereinafter described, may be of the usual or any suitable construction and may be held to the door in any suitable manner.

To permit inspection of the fuel bed without opening the fire door, I preferably provide the door with an elongated rectangular opening 6, as shown, although it will be understood that the opening 6 may be of any other suitable shape. A substantially rectangular frame 7 is held to the outer side of the door 1 and extends about the edges of the opening 6, said frame 7 being preferably provided with flanges 8 and 9 fitting within the opening 6. The frame 7 is fixed to the 95 door 1 in any suitable manner and serves as a support for the observation device and also to reinforce the door. It will be understood, however, that the parts of the observation device may be supported directly on the 100 door 1, or in any other suitable manner, if desired.

A metallic plate 10 is pivotally held in the frame 7 by means of pins 11 extending through ears 12 formed on the side members 105 of the frame adjacent the lower ends thereof, said pins extending into suitable sockets or journals in the side edges of the plate 10. The plate 10 normally closes the opening 6 in the fire door. A rectangular frame 13 is 110 held to the lower edge of the plate 10 and extends outwardly substantially at a right

angle with said plate, said frame 13 being preferably cast, or otherwise formed, integrally with the plate 10. A sheet or plate 14 of transparent material is held in the frame 13. I prefer to employ a plate of blue glass which may be inserted in the frame from the outer edge thereof through a slot 27 and held in place by a cotter pin 28, or other suitable means, the inner and side edges of the glass plate being seated in suitable channels in the edges of the frame. The use of blue glass for the transparent panel permits a clear view of the condition of the fuel bed, as the blue glass eliminates the yellow rays from the fire and protects the eyes from the glare of the flames, thus permitting a clear view of the coals and enabling the stoker to readily detect thin spots in the fuel bed, or other conditions detrimental to the efficiency of the fire.

The protecting lining 5 is formed with an elongated rectangular opening 15 opposite the opening 6 in door 3, normally closed by a pivoted lining section 16. The frame 7 is formed with a pair of inwardly extending arms or brackets 17, preferably forming extensions of the flanges 9, and the movable section 16 of the lining is formed with a pair of arms or brackets 18 at opposite sides thereof adjacent its upper edge. The arms 18 extend forwardly between the arms 17 and are pivotally connected therewith by horizontal pivot pins or bolts 19 extending through the arms 17 adjacent their inner ends and passing through the arms 18 intermediate their ends and preferably adjacent to the movable section 16 of the protecting lining.

The upper edges of the arms 18 are curved or shaped to form cam surfaces 20 engaging the curved or cam edges 21 of segmental plates or webs 22, cast integrally with, or otherwise held to the plate 10 and frame 13 at opposite sides thereof. The lower edge 45 of the movable section 16 of the lining is formed with rearwardly extending enlargements or projections 23 to increase the weight of that portion of the section 16 which extends below the pivotal point of said section. It will be observed also that the pivotal point of the section 16 is above the middle thereof and that the lower portion of the section therefore overbalances the upper portion and tends to normally move 55 the section to a vertical position to fill the opening 15 in the lining 5.

The frame 13 carrying the transparent plate 14 is provided with a suitable handle 24 to permit said frame and the opaque metal plate 10 to be readily rocked about the pivots 11 to cause either the plate 14 or plate 10 to register with the opening 6 in the door. When the frame 13 and plate 14 are swung upwardly the plate 10 moves inwardly and downwardly away from the

opening 16, and the movable section 16 of the door lining is simultaneously swung upwardly away from said opening by action of the cam edges 21 of plates 22 which engage the cam edges 20 of arms 18 and depress said arms. The parts are preferably so shaped and proportioned that plate 10 extends below its pivotal point when the glass plate 14 is in register with opening 6 and the plates or cams 22 are at the rear of the pivotal point 13, so that the parts will remain in the position shown in Figs. 2 and 4 until the handle 24 is again depressed. When the handle 24 is depressed it will be seen that the transparent plate 14 will be 80 swung downwardly and outwardly away from opening 6 to a position in which it will not be subjected to the heat of the combustion chamber, and that the opening 6 will be closed by the metal plate 10. It will be 85 obvious that when the plate 10 is swung upwardly and outwardly the arms 18 will be free to swing upwardly and outwardly about the pivots 19, and that the movable section 16 of the door lining will be automatically 90 shifted to close the opening 15 in the lining 5 by reason of the overbalancing weight of the lower portion of said section. The weight of frame 13, plate 14, and cam plates 22, serves to hold the plate 10 in its raised 95 position after the handle 24 is depressed. It will also be observed that when the plate 10 is in position to close opening 6 the forward ends of arms 18 engage the rear edges of cam plates 22 and serve to assist in holding plate 10 in raised position. If desired, the section 16 of the lining may be provided with a forwardly extending lug or projection 26 adjacent its upper edge, said projection being 100 preferably provided with a beveled face, as shown, adapted to be engaged by the upper edge of plate 10 in case said movable lining section should fail to swing downwardly when the plate 10 is swung upwardly as heretofore described. It will be obvious 105 that, should the lining section 16 fail to swing downwardly as plate 10 is moved upwardly, the upper edge of plate 10 will engage the projection 26 and rock the section 16 about its pivot, thus insuring movement 110 of section 16 to its normal vertical position when the plate 10 is moved to closed position.

From the foregoing it will be observed 115 that simple means has been provided whereby the condition of the fuel bed of a furnace may be observed without the necessity of opening the fire door, thus avoiding loss of heat and impairment of the efficiency of the fire due to frequent opening of the fire door 120 for purposes of inspection, and also avoiding subjecting the stoker to the direct heat of the fire.

It will also be observed that means has 125 been provided whereby the stoker or fireman 130

may clearly see the fuel bed, since the blue glass observation panel filters out the yellow rays, eliminates the glare from the flames, and protects the eyes of the stoker 5 from the intense heat of the combustion chamber. It will be seen also that the fire may be inspected without admitting a large influx of cold air into the combustion chamber. This is highly important, not only because the admission of cold air impairs the efficiency of the fire, but also because the admission of cold air causes the production of considerable smoke and soot in the combustion chamber, which results in obscuring the 10 view of the fuel bed, making it almost impossible to detect the presence of thin spots therein or other conditions liable to impair the efficiency of the fire. The use of a transparent observation panel also enables the 15 stoker to closely approach the fuel bed and carefully observe the condition thereof.

It will be observed also that a feature of importance lies in embodying the transparent-panel-door and the opaque-fire-resistant-door in a single rockable device pivoted on a horizontal axis extending along the lower edge of the peep-opening in the furnace wall, the two doors lying at approximately right angles to each other, so 20 that when the transparent door is in position to perform its function, the opaque door will be entirely out of line or register with the peep-opening and will therefore not be in a position to obscure a clear view of the 25 fuel bed. This construction is not only simple and durable, but is further advantageous in that to shift the transparent door into position for use it is simply necessary for the furnace man to tilt the rockable device 30 by manually lifting the transparent door, so that by a very simple and quick operation the attendant may frequently inspect the fuel bed. It will be seen also that the segmental side walls 22 which connect the ends 35 of the door serve not only to brace the doors and thus provide a strong structure, but also to cut off the ingress of air not only during the shifting of the doors but also after they 40 are shifted.

It will be seen also that a feature of importance lies in having both doors 10 and 13 wide enough to strike and bear against the upper edge of the peep-opening when either door is shifted to closure position, thus not 45 only providing a simple stop for each door but also insuring a complete closing of the peep-opening in either position. It will be seen also that the juncture-corner of the two doors is beveled off at 13° so that, whichever 50 door is positioned for functioning, this beveled surface will swing into position to close that portion of the peep-opening which lies below the axis of the rockable device, thereby insuring complete closure of the 55 peep-opening along the lower edge thereof.

What I claim is:

1. The combination with a furnace whose wall is provided with a peep-opening, of a rockable structure pivoted in said opening on an axis extending along one edge thereof, 70 said structure embodying a pair of doors connected together at the pivotal point, one door being fire-resistant and opaque and the other door being provided with a transparent panel, whereby either door may be shifted to close the peep-opening and the other door be simultaneously shifted to a position out of alinement therewith.

2. The combination with a furnace whose wall is provided with a peep-opening, of a 80 rockable structure pivoted in said opening on an axis extending along one edge thereof, said structure embodying a pair of doors connected together at the pivotal point, one door being fire-resistant and opaque and the other door being provided with a transparent panel, whereby either door may be shifted to close the peep-opening and the other door be simultaneously shifted to a 85 position out of alinement therewith, the doors being wider than the peep-opening to permit their free edges to contact respectively with the inner and outer faces of the furnace wall along the edge of the peep-opening opposite the pivotal point. 95

3. The combination with a furnace whose wall is provided with a peep-opening, of a rockable structure pivoted in said opening on an axis extending along one edge thereof, 100 said structure embodying a pair of doors connected together at the pivotal point, one door being fire-resistant and opaque and the other door being provided with a transparent panel, whereby either door may be shifted to close the peep-opening and the other door be simultaneously shifted to a position out of alinement therewith, the ends 105 of said two doors being connected by segmental walls, for the purpose set forth.

4. The combination with a furnace whose 110 wall is provided with a peep-opening, of a rockable structure pivoted in said opening on an axis extending along one edge thereof, said structure embodying a pair of doors connected together at the pivotal point, one door being fire-resistant and opaque and the other door being provided with a transparent panel, whereby either door may be shifted to close the peep-opening and the other door be simultaneously shifted to a 115 position out of alinement therewith, the corner formed by the juncture of the two edges of the door at the pivotal point being beveled off to insure a complete closure of the peep-opening along its pivotal edge in either position of the rockable device.

5. In combination with a furnace having an opening through which the burning fuel may be inspected, a rockable device pivotally mounted in the lower part of said open- 130

- ing and embodying two plates lying substantially at right angles to each other, one of these plates being opaque and fire-resistant and the other being transparent, the 5 fire-resistant plate lying inside of the furnace and the transparent plate lying outside of the furnace, whereby by simply rocking said device on its pivot either one of said plates may be brought into position to 10 cover this opening, for the purpose set forth.
6. The combination of a furnace having a metallic casing and an inner protecting lining for said casing, and means whereby adjacent portions of said casing and lining 15 may be simultaneously shifted to permit inspection of the combustion chamber when the fire door of the furnace is closed.
7. The combination of a furnace having a metallic casing and an inner protecting 20 lining for said casing, means whereby adjacent portions of said casing and lining may be shifted to permit inspection of the fuel bed, and a sheet of transparent material held to the casing exteriorly thereof 25 and adapted to extend over the opening formed by shifting said portions of the casing and lining to permit inspection of the fuel bed without admitting cold air to the combustion chamber.
8. The combination of a furnace having a metallic casing, an inner protecting lining 30 for said casing, means whereby adjacent portions of said casing and lining may be simultaneously shifted to permit inspection 35 of the combustion chamber, a sheet of transparent material, and means for shiftably supporting said sheet of transparent material on the casing to adapt said transparent sheet to be moved to cover the ob- 40 servation opening formed by shifting said sections of the casing and lining.
9. The combination of a furnace having a metallic casing, an inner protecting lining 45 for the casing, said casing and lining being provided with oppositely disposed shiftable portions, a shiftable frame held to the casing, a sheet of transparent material held in 50 said frame, and means whereby said frame and the shiftable portions of the casing and lining may be simultaneously moved to form an observation opening through said casing and lining closed by said sheet of transparent material.
10. The combination of a furnace having 55 a metallic casing, an inner protecting lining for the casing, said casing and lining being provided with oppositely disposed shiftable portions, a shiftable frame held to the casing, a sheet of transparent material held in

said frame, means whereby said frame and the shiftable portion of the casing may be moved to cover an observation opening in the casing with said shiftable portion of the casing and said sheet of transparent material alternately, and means controlled by the 65 movement of said frame and shiftable portion of the casing for moving said shiftable portion of the lining.

11. The combination of a furnace having a metallic casing, an inner protecting lining 70 for the casing, said casing and lining being provided with oppositely disposed shiftable portions, a shiftable frame held to the casing exteriorly thereof, a plate of blue glass held in said frame, and means whereby said 75 frame and the shiftable portions of the casing and lining may be simultaneously moved to form an observation window through which the fuel bed may be inspected.

12. A metallic fire door for a furnace having an observation opening therein, an inner protecting lining for the door having a shiftable portion normally held opposite said opening, a shiftable metal plate held to the door and normally closing said observation 85 opening, and means whereby said plate and the shiftable portion of the lining may be moved to permit inspection of the fuel bed through said opening.

13. A metallic fire door for a furnace having an observation opening therein, an inner protecting lining for the door having a shiftable portion normally held opposite said opening, a shiftable metal plate held to the door and normally closing said observation 95 opening, and means controlled by shifting said metal plate to cover and uncover said opening for simultaneously moving said shiftable portion of the lining.

14. A metallic fire door for a furnace having an opening therein through which the fuel bed may be inspected, an inner protecting lining for the door having a shiftable portion opposite said opening, a metal plate pivotally held to the door adapted to 105 normally close said opening, a frame mounted to move with said metal plate, a sheet of glass held in said frame adapted to cover said opening when the metal plate is moved to uncover the opening, and means for automatically moving said shiftable portion of the lining out of register with said opening when the glass sheet is moved to cover the opening.

In testimony whereof I hereunto affix my 115 signature.

MALCOLM CURRY.
